UNITED STATES PATENT OFFICE.

CYRUS S. WERT, OF KENDALLVILLE, INDIANA.

MOLD.

965,349.

Specification of Letters Patent. Patented July 26, 1910.

Application filed August 30, 1909. Serial No. 515,238.

To all whom it may concern:

Be it known that I, CYRUS S. WERT, a citizen of the United States, residing at Kendallville, in the county of Noble and State 5 of Indiana, have invented certain new and useful Improvements in Molds; and I do declare the following to be a full, clear, and exact description of the invention, such as will enable others skilled in the art to which 10 it appertains to make and use the same.

My invention relates to molds and particularly to circular molds for making sections of sewers, cesspools, catch basins, wells, silos and the like.

15 The object of the invention is to provide a simple, cheaply constructed, and efficient mold of this character which may be quickly operated to form the section and which can be operated to readily disconnect the section.

20 With this and other objects in view, the invention consists of certain novel features of construction, combination and arrangement of parts as will be more fully described and particularly pointed out in the appended 25 claim.

In the drawings, Figure 1 is a top plan view of the mold ready to be filled; Fig. 2 is a similar view of the mold shown in open position; Fig. 3 is a perspective view of one 30 of the sections formed; Fig. 4 is an enlarged perspective view of a portion of one side of the mold showing the reinforcement; Fig. 5 is a top plan view, showing how a plurality of the blocks look when associated.

35 Referring more especially to the drawings, 1 and 2 represent the sides of the device which are preferably composed of 10 gage sheet steel, reinforced throughout their length by tee-iron braces, 3. These sides 40 have one end connected with the end piece 4 by hinges 5, which permit free swinging of the sides upon the ends so as to release the same from the molded article.

Hinged to the opposite end of the side 2, 45 by a hinge 6, is an end piece 7, which carries the latching bar 8, adapted to be straddled by the latch 9, carried upon the side 1. This latching bar is held rigidly upon the tee-rib 3, and has a pin 10, extending through its 50 forward end adapted to engage the cam sur-

face 11, upon the latch bar 8 so as to forcibly bring the end 7 into engagement with the side 1. The end 4 is provided with an outwardly extending ridge 12, adapted to form an outwardly projecting rib 13, upon the section 14, and the end 7 is provided with an inwardly projecting offset 15, adapted to form a socket 16, upon the section 14, which is constructed to receive the rib of an adjoining section. The sides of the device 60 may be formed upon the arc of any circle and may be separated by ends having sufficient length to produce the width desired.

From the foregoing description, taken in connection with the accompanying drawing, 65 the construction and operation of the invention will be readily understood without requiring a more extended explanation.

Various changes in the form, proportion and the minor details of construction may be 70 resorted to without departing from the principle or sacrificing any of the advantages of this invention as defined in the appended claim.

Having thus described my invention, what 75 I claim is:

A mold comprising a pair of arcuate sides, reinforcing ribs carried by the sides, an end member hinged to both sides and having an outwardly projecting offset adapted to produce a rib upon the molded article, a second end hinged to one of said sides at the opposite end thereof, and having an inward offset to produce a socket in the molded article, a latching bar pivoted to said second end adjacent its hinged connection and having a cam face, a guiding pin therefor, a latching loop pivoted to the reinforcing rib on one side to engage over the latching bar, and a pin passed through the latching loop and adapted to ride upon the cam face whereby the end is forced into engagement with the side and locked.

In testimony whereof I have hereunto set my hand in presence of two subscribing witnesses.

CYRUS S. WERT.
